DRY-CELL BATTERY.

1,366,191.

Specification of Letters Patent. Patented Jan. 18, 1921.

Application filed December 17, 1919. Serial No. 345,644.

To all whom it may concern:

Be it known that we, HARRY M. KORETZKY and BORIS H. TEITELBAUM, citizens of the United States, and residents of the city of 5 New York, borough of Brooklyn, in the county of Kings and State of New York, have invented a new and Improved Dry-Cell Battery, of which the following is a full, clear, and exact description.

10 This invention relates to dry cell batteries of the same general type as are covered by our co-pending application Serial No. 345,642 of even date herewith, in which the electric agents of the battery are normally spaced from each other or inactive for an 15 indefinite length of time, up to the time the battery is to be put into use, and whereby the devices are not subject to deterioration during the interval of time elapsing between 20 the time of manufacture and the time of use.

Among the objects of this invention is to provide a battery of a somewhat more compact form in idle condition than in the other 25 form of our invention above referred to, the construction in this instance being such that the device is of practically the same length whether idle or active, but the zinc element of the construction is carried in a position 30 spaced outward from the other parts of the device and consists of a split tube.

With the foregoing and other objects in view the invention consists in the arrangement and combination of parts hereinafter 35 described and claimed, and while the invention is not restricted to the exact details of construction disclosed or suggested herein, still for the purpose of illustrating a practical embodiment thereof reference is had to the accompanying drawings, in which like 40 reference characters designate the same parts in the several views, and in which—

Figure 1 is a vertical sectional view of a preferred embodiment of this invention in 45 idle condition.

Fig. 2 is a similar view of the same structure in active condition.

Fig. 3 is a detail perspective view of the zinc member.

50 Fig. 4 is a vertical sectional view of a modification of the invention designed especially for large single cell batteries.

Referring now more particularly to the drawings we show in Figs. 1 and 2 a battery 55 comprising a depolarizing member 10

fitted upon a carbon stick 11 the upper or outer end of which is sealed rigidly in a bituminous seal 12 and fitted with a contact cap 13 projecting beyond the seal. The fibrous paper washer 14 is preferably used 60 against the inner surface of the seal 12. The depolarizing agent is preferably spaced from the surrounding wall of a container 15 which may be made of any suitable bibulous paper or the like. The space between the members 10 and 15 is preferably 65 filled by means of electrolyte 16 which may have the consistency of jelly and retained in place by means of a paper closure 17 at the bottom. 70

Loosely surrounding the container 15 is a second container 18 which likewise may be made of paper or some other suitable cheap material and substantially coextensive with the inner container 15. The outer 75 container 18 may have a central hole 19 at its lower end within which is fitted a zinc plate 20 having an upturned periphery. With the parts arranged as thus far described there is no chemical or electrical 80 action possible during any reasonable time preliminary to the putting of the battery into use, because the metallic element 21 is wanting.

The metallic member above referred to 85 consists of a split zinc tube preferably of a length substantially equal to the length of the inner member 15 and so formed as to contract into a smaller radius than either of the paper containers so that when it is 90 sprung upon the outside of the container 18 it will be carried in such idle position indefinitely by friction. A paper cap, or its equivalent, 22 slipped upon the upper end of the entire device as shown in Fig. 1 serves 95 to hold the parts intact and to protect the various elements from moisture, dust, or other conditions.

When the battery is to be put into use the cap 22 is stripped off and discarded 100 and the zinc tube 21 will be slipped endwise from its place or detached from the container 18. The inner container with its contents is then soaked for a few moments in a weak solution of acetic acid or its 105 equivalent, and then the zinc tube 21 is sprung sufficiently to slip it upon the wet member, and finally the parts as thus assembled are slipped into the outer container 18 as shown in Fig. 2. The soaking serves 110

to initiate the electrical action between the depolarizing member and the zinc tube through the electrolyte. The contact cap 13 is adapted to project through the hole 19 5 and against the zinc plate 20 of the next adjacent cell in a multiplicity of cells arranged in series.

The battery of Fig. 4 in most respects is similar to that of Fig. 2, but the depolarizing member 10^a is designed to substantially fill the space within the inner container 15, and the carbon stick 11^a differs from the one above described in having a binding screw 23 fitted in its upper end while the 10 zinc tube 21^a is fitted with a corresponding binding screw 24. As above described the tubular member 21^a is carried normally or in inactive position on the outside of the container 18 in which position there is no 15 electrical action nor chemical deterioration. When the battery is to be put into use the inner container with its contents, as above described, is soaked in a suitable solution for the purpose of initiating the electrical 20 action which takes place and continues 25 when the zinc tube 21^a is slipped within the container 18.

We claim:

1. In a dry cell battery, the combination 30 of a depolarizing member, a bibulous container therefor, a metallic pole member, and means between the bibulous member and the pole member serving to normally hold the

metallic member spaced outward from the bibulous container, but adapted to receive 35 the pole member within it when the battery is put into use.

2. In a dry cell battery, the combination of a depolarizing member, a bibulous container therefor, means to seal and hold the 40 depolarizing member in fixed position within the bibulous container, a paper container loosely surrounding the bibulous container, and a split tubular metallic member carried normally in idle position on the 45 outside of the paper container but adapted to be slipped within the paper container for direct coaction with the bibulous container, substantially as set forth.

3. In a dry cell battery, the combination 50 of a bibulous container adapted to be readily saturated when soaked in a liquid, a depolarizing member carried within said container, a contact member at the exposed end of the depolarizing member, a paper container loosely fitted around the bibulous container, a split tubular zinc member carried in idle position around the paper container and thereby spaced from the bibulous container, and discardable means serving to hold the parts in the relation stated, 55 said tubular member being adapted to be slipped between the two containers after the bibulous container is soaked as specified.

HARRY M. KORETZKY.
BORIS H. TEITELBAUM.
